FIG. 1

FIG. 2

FIG. 3

FIG. 4

INVENTOR.

Roscoe G. Conklin,

BY

James J. Sheely, ATTORNEYS

UNITED STATES PATENT OFFICE.

ROSCOE G. CONKLIN, OF OMAHA, NEBRASKA.

FLAGSTAFF.

Application filed February 24, 1925, Serial No. 11,320. Renewed March 18, 1927.

My present invention pertains to flagstaff holders and it contemplates the provision of a device through the medium of which a flag or other emblem may be displayed on a window, post, porch or other place and this without detracting from the appearance of the building and at the same time assuring the firm and rigid support of the staff regardless of wind or other climatic conditions.

The invention further contemplates the provision of a bracket that is simple and inexpensive to produce, readily and easily attached and one that because of its finished appearance will in no way detract from the appearance of the object to which the holder is attached.

Other objects of the invention will be readily understood from the following description and claim when the same are read in connection with the drawings accompanying and forming part of this specification in which:—

Figure 1 is a view partly in side elevation and partly in section showing my novel device attached to a post or side of a window frame or the like.

Figure 2 is a side elevation showing the manner in which the bracket may be secured on a flat surface such as the sill of a window casing.

Figure 3 is a rear elevation of the device.

Figure 4 is a view similar to Figure 1 without the staff arranged therein and showing the support of the bracket partly in section.

Figure 5 is a perspective view looking down on the bracket and from a point approximately at the rear thereof.

Similar numerals of reference designate corresponding parts in all the views of the drawings.

My novel device comprises the bracket that is indicated as a whole by B and consists of the flat body portion 1 that is increased in width toward the upper end thereof and for the purpose of clearness may be termed the web and formed integral on one end of the portion 1 is an angular bent flat portion 2 that is provided with the apertures 3 that receive the fastening means 4. The fastening means may take in to the support S of Figure 1 that may be a post, or other upstanding element while in Figure 2 the support S may be flat as illustrated. The body portion is provided on the surface op-

posite the element 2 with the rolled angular-tubular portion 5 that is bent at 6 to provide a rib 7. This rib extends approximately the full length of the rolled portion and forms 60 an interior rib or kerf; the purpose of which will be clearly understood from the further description of the practical use of the device. Formed on the rolled portion 5 and adapted to be soldered or otherwise secured 65 interiorly of the rolled portion 5 and preferably opposite the rib 7 is a spring clip 9 that straddles the upper end of the rolled portion 10, while at the lower end of the roll I bend same inwardly for a very slight 70 distance to enable same to rest flush with the angular bent portion 2. This provision is necessary in order that the bent portion 2 will rest flat on the support S for otherwise if the rolled end was not bent at the point 8 75 a firm grip on the support could not be had by the fastening means 4 without marring the surface due to the end 8 if unbent contacting said surface and digging into same.

In the practical use of the device, the same 80 is secured either on a flat surface or a surface such as is shown in Figure 1 and the pole P is forced into the upper end of the rolled portion of the member 1 where it is firmly gripped and held in proper position by 85 means of the ribs 7 and spring 9. Manifestly the rolled portion 5 is open at its lower end in order to permit of self draining of the rolled portion.

The bracket or support when once fastened 90 to a post or window casing or the like is practically to stay and need not be removed unless desired and it will display a flag at an angle of approximately 39 degrees whether it is attached to a post or a window sill, 95 while the spring placed in the top of the socket will prevent the wind from raising the flag out of the socket. The bracket when finished is enameled to prevent rust and is preferably formed of galvanized iron sheet- 100 ing which is strong and durable and yet has the added feature of being inexpensive and because it is made of this material castings are not necessary for production of the brackets but on the other hand inexpensive 105 stamping may be resorted to.

Having described my invention, what I claim and desire to secure by Letters-Patent is:—

In a flagstaff holder, the combination of a 110 tubular body portion open at its ends an inwardly projecting portion at one end, said

body portion comprising a tubular body member in the form of a coil in cross-section the interior edge of said coiled portion projecting radially inwardly to form a continuous interior longitudinal rib, a spring clip extending into the tubular body portion, a web formed integral on the body por-

tion and terminating in a base portion whereby the holder is formed of a single piece of material. ¹⁰

In testimony whereof I have hereunto set my hand:

ROSCOE G. CONKLIN.
